UNITED STATES PATENT OFFICE

156,300

DESIGN FOR A BANK AND CLIMB GYRO INSTRUMENT

Harry C. Wendt, Lynnfield, and Matthew A. Jordan, Saugus, Mass., assignors to General Electric Company, a corporation of New York

Application August 15, 1947, Serial No. 140,896

Term of patent 7 years

(Cl. D52—1)

To all whom it may concern:

Be it known that we, Harry C. Wendt and Matthew A. Jordan, citizens of the United States, residing respectively at Lynnfield, in the county of Essex, State of Massachusetts, and Saugus, in the county of Essex, State of Massachusetts, have invented a new, original, and ornamental Design for a Bank and Climb Gyro Instrument, of which the following is a specification, reference being had to the accompanying drawing forming a part thereof.

Figure 1 is a perspective view of a bank and climb gyro instrument showing our new design.

Figure 2 is a front elevation.

The characteristic features of our design reside in the portion shown in solid lines.

We claim:

The ornamental design for a bank and climb gyro instrument, as shown and described.

HARRY C. WENDT.
MATTHEW A. JORDAN.
